US00D993289S

(12) **United States Design Patent** (10) Patent No.: **US D993,289 S**
Tsujimoto et al. (45) Date of Patent: ** Jul. 25, 2023

(54) **WASHING MACHINE FOR MACHINED PARTS**

(71) Applicant: **SUGINO MACHINE LIMITED**, Uozu (JP)

(72) Inventors: **Kei Tsujimoto**, Tokyo (JP); **Kosuke Wakao**, Tokyo (JP); **Taiki Matsui**, Uozu (JP); **Takuya Aoki**, Uozu (JP); **Akihiro Ishitani**, Uozu (JP)

(**) Term: **15 Years**

(21) Appl. No.: **35/512,341**

(22) Filed: **Feb. 10, 2021**

(80) **Hague Agreement Data**

Int. Filing Date: **Feb. 10, 2021**

Int. Reg. No.: **DM/212759**

Int. Reg. Date: **Feb. 10, 2021**

Int. Reg. Pub. Date: **Aug. 13, 2021**

(30) **Foreign Application Priority Data**

Oct. 7, 2020 (JP) ..... 2020-021530 D

(51) LOC (14) Cl. **15-09**

(52) U.S. Cl.

USPC **D15/122; D32/1**

1.16: Top

1.17: Cross sectional

1.18: Perspective

(Continued)

Fig. 1.7 is a front view showing the state in which the shutter on the front panel is open; figs. 1.11, 1.12, 1.13, 1.14, 1.15 and 1.16 are views showing the state in which the shutter on the left side panel is open and the arm comes out therefrom; fig. 1.18 is a perspective view showing the state in which the shutter on the right side panel is open and the arm comes out therefrom; fig. 1.9 is a cross-sectional view taken along the A-A line shown in the fig. 1.6; fig. 1.10 is a cross-sectional view taken along the B-B line shown in the fig. 1.7; fig. 1.17 is a cross-sectional view taken along the C-C line shown in the fig. 1.15. Features shown in broken lines form no part of the claimed design.

1 Claim, 18 Drawing Sheets
